UNITED STATES PATENT OFFICE.

WILLIAM W. DEAN, OF CHICAGO, ILLINOIS, ASSIGNOR TO KELLOGG SWITCH-BOARD AND SUPPLY COMPANY, OF CHICAGO, ILLINOIS, A CORPORATION OF ILLINOIS.

TELEPHONE-TRANSMITTER.

SPECIFICATION forming part of Letters Patent No. 687,499, dated November 26, 1901.

Application filed March 22, 1901. Serial No. 52,276. (No model.)

To all whom it may concern:

Be it known that I, WILLIAM W. DEAN, a citizen of the United States, residing at Chicago, in the county of Cook and State of Illinois, have invented a certain new and useful Improvement in Telephone-Transmitters, of which the following is a full, clear, concise, and exact description, reference being had to the accompanying drawings, forming a part of this specification.

My invention relates to a telephone-transmitter of the granular type, in which a body of granular carbon or similar material is interposed between two electrodes adapted to partake of relative movement to vary the resistance between the electrodes.

It is the object of my invention to provide a telephone of this type which will be simple and compact in structure and which will effectively prevent the "packing" of the granules, thereby overcoming an objection which is incident to most of the granular telephones as commonly constructed heretofore.

In accordance with my invention I provide a suitable diaphragm adapted to be vibrated by the vocal organs of the speaker, the diaphragm carrying a suitable recess or chamber for the granules, in which chamber is located one of the electrodes of the telephone. A supplemental diaphragm is associated with the main diaphragm and peripherally attached thereto, the second electrode of the microphone being associated with said supplemental diaphragm in an intraperipheral position—that is, associated with the supplemental diaphragm within the periphery thereof and preferably at the center of the supplemental diaphragm. The supplemental diaphragm co-operates in maintaining the granules within the chamber, and the electrode associated therewith is mounted in any suitable manner, so that as the main diaphragm vibrates the electrode will partake of relative movement to vary the resistance of the microphone. I preferably support the electrode which is associated with the supplemental diaphragm upon a rigid abutment or support, as I find this structure to give the best results, although the employment of a rigid abutment or support is not essential to the operation of the telephone.

I have illustrated my invention in the accompanying drawings, in which—

Figure 1 is a sectional view showing my invention. Fig. 2 is a view showing the parts 55 therein in detached position. Fig. 3 is a rear view of the main diaphragm and parts associated therewith. Fig. 4 is a view showing the rear of the assembled transmitter.

Like letters refer to like parts in the several figures.

A support or front piece *a* of any desired form carries the usual mouthpiece *a'* and supports the inclosing casing *a''*. The main diaphragm *b* carries upon the periphery the 65 usual packing-ring *b'*, of rubber or similar material, and is adapted to be yieldingly pressed against the face or support *a* by means of the springs *c c'*, having pads, of rubber or similar material, upon the ends. As 70 illustrated, the diaphragm *b* has the central portion *b*² laterally deflected or displaced to form a recess or chamber *b*³. Within this chamber is supported one of the electrodes of the microphone, which preferably takes 75 the form of a metal plate *d*, having a threaded shank *d'*, which passes through a central opening in the part *b*², upon which threaded shank a nut *d*² is adapted to be screwed to securely bind the electrode to the diaphragm. 80 Upon the face of the plate *d* a carbon block or disk *d*³ is mounted, preferably by electroplating the face of the carbon disk and then soldering the same to the plate *d*. While I 85 preferably form the electrode of carbon and metal, as above described, it will be understood that the electrode may be formed in any other preferred manner. The side walls of the chamber may be covered with lacquer or suitable material to insulate the same from 90 the granules within the chamber, or they may be depended upon to constitute the electrode, though not so efficiently as with the construction described. The supplemental diaphragm *e*, of mica or other suitable material, is secured at its periphery to the edge of the chamber by means of a ring *e'* and the screws *e*² *e*² or in any suitable manner, the supplemental diaphragm *e* thus serving to close the chamber. The supplemental diaphragm *e* carries 100 a central opening, through which the shank *f'*, connected with the plate *f*, is adapted to pass. The shank *f'* also passes through a bore in the block *g*, which has an enlarged head *g'*. A nut *g*² screws upon the threaded 105 end of the shank *f'* and serves to clamp the

central portion of the supplemental diaphragm *e* between the head *g*' and the plate *f*. Upon the face of the plate *f* a carbon block or disk *d*⁴ is mounted in a manner similar to the mounting of the disk *d*³. The electrode associated with the supplemental diaphragm is of less diameter than the chamber, so that the granules may rest not only between the two electrodes, but also upon the exterior of the periphery of the electrode associated with the supplemental diaphragm. A transverse support or bridge-piece *h* is mounted at the ends upon the base *a* and carries at the center an opening to receive the shank of the block *h*', said block *h*' being preferably rigidly secured to the bar or support *h*. The part *g* may be adjusted in position within the bore of the block *h*' and clamped in the adjusted position by means of the set-screw *h*².

20 When air-currents due to the voice impinge against the main diaphragm *b*, said diaphragm is set in vibration, thereby causing the electrode carried by the main diaphragm to approach the stationary electrode and to recede therefrom to vary the resistance through the microphone. Since the chamber containing the granules is carried upon the main diaphragm, whereby the granules are subjected to continual vibration, the tendency of the granules to pack is effectively prevented.

25 I have mentioned carbon granules as the specific resistance-varying medium to be used with this transmitter, because at present this seems to be the best suited for practical use. There are, however, other well-known forms of comminuted conducting material the use of which clearly lies within the scope of my invention.

30 While I have illustrated my invention in connection with the details of construction which have been worked out for commercial purposes, it will be understood that they are susceptible of various modifications, and I do not desire to confine myself to the precise details of construction shown. For instance, instead of forming the chamber for the granules by laterally displacing the central portion of the main diaphragm, the chamber may be formed in any other manner and need not form an integral part of the diaphragm. Moreover, the mounting of the electrode which is associated with the supplemental diaphragm is susceptible of considerable variation without departing from the spirit of my invention, and many other changes could be made which will readily suggest themselves to those skilled in the art.

Having described my invention, what I claim as new, and desire to secure by Letters Patent, is—

1. In a telephone-transmitter, the combination with a suitable diaphragm, of a chamber for the granules carried thereon, an electrode within said chamber and moving with said diaphragm, a supplemental diaphragm peripherally secured to said main diaphragm,

and a second electrode associated with said supplemental diaphragm in an intraperipheral position, substantially as described. 70

2. In a telephone-transmitter, the combination with a suitable diaphragm, of a chamber for the granules carried thereon, an electrode within said chamber and partaking of the movement of said diaphragm, a supplemental diaphragm peripherally connected with said diaphragm, a second electrode associated with said supplemental diaphragm in an intra-peripheral position, and an abutment for said second electrode mounted in a stationary position, substantially as described. 75 80

3. In a telephone-transmitter, the combination with a diaphragm having a central portion relatively displaced to form a chamber for the granules, of an electrode within said chamber and partaking of the movement of the diaphragm, a supplemental diaphragm peripherally secured to the main diaphragm and a second electrode associated with said supplemental diaphragm in an intra-peripheral position, substantially as described. 85 90

4. In a telephone-transmitter, the combination with the diaphragm, *b*, having the central portion, *b*², laterally deflected to form a chamber for the granules, of an electrode mounted within said chamber and having a shank passing through an opening in said part, *b*², a fastening device engaging said shank, the supplemental diaphragm, *e*, the ring, *e*', for securing the periphery thereof to the main diaphragm, *b*, the stationary support, *h*, the block, *g*, adjustably movable relatively to said support, *h*, and the electrode carried upon said part, *g*, and associated with said supplemental diaphragm, substantially as described. 100 105

5. In a telephone-transmitter, the combination with a sound-receiving diaphragm having a forwardly-deflected portion, of an electrode carried in said forwardly-deflected portion, and a second electrode adapted to co-operate with said first-mentioned electrode through the medium of comminuted conducting material, substantially as described. 110

6. In a telephone-transmitter, the combination with a diaphragm comprising a sheet of material having a portion laterally deflected to form a recess or chamber, of an electrode within the chamber and moving with said diaphragm, a second electrode, a suitable support for said second electrode, and comminuted material between the two electrodes and co-operating therewith, substantially as described. 115 120 125

7. In a telephone-transmitter, the combination with a diaphragm comprising a sheet of material having a portion deflected to form a recess or chamber, of an electrode within the chamber and moving with the diaphragm, a stationary support, a second electrode mounted on said support and extending into said recess or chamber, and comminuted material in said recess or chamber between said electrodes, substantially as described. 130

8. In a telephone-transmitter, the combination with a suitable sound-receiving diaphragm carrying a laterally-deflected chamber for the granules, of an electrode within said chamber and moving with said diaphragm, a supplemental diaphragm adapted to close said chamber, and a second electrode associated with said supplemental diaphragm in an intraperipheral position, substantially as described.

9. In a telephone-transmitter, the combination with a metallic diaphragm carrying a forwardly-deflected chamber, an electrode within said chamber and having a shank passing through an aperture in the bottom thereof, means for securing said shank to the wall of the chamber whereby the electric circuit is completed therethrough, a second electrode coöperating with the first-mentioned electrode, and comminuted material between said electrodes, substantially as described.

10. In a telephone-transmitter, the combination with a diaphragm having a chamber for the granules carried thereon, of a supplemental diaphragm peripherally secured to said main diaphragm, a block fitting against the outer face of said supplemental diaphragm, a plate fitting against the inner face of said diaphragm, and means to clamp said plate and block together upon the diaphragm, substantially as described.

11. In a telephone-transmitter, the combination with a main diaphragm, a chamber or recess carried thereby, a supplemental diaphragm peripherally secured to said main diaphragm, a block pressing against the outer face of said supplemental diaphragm, a plate similarly located with reference to the inner face of the supplemental diaphragm and having a shank extending through a bore in said block, means to secure the shank so as to clamp the plate and block together upon the said diaphragm, and a support for the block, substantially as described.

12. In a telephone-transmitter, the combination with a diaphragm having a central portion laterally deflected to form a recess or chamber, an electrode in the chamber and movable therewith, a second electrode, a suitable support therefor, and comminuted material between said electrodes, substantially as described.

13. The combination with a vibratory member forming a chamber, of an electrode adapted to vibrate therewith, a supplemental member to close said chamber, a second electrode associated with said supplemental member and adapted to be rigidly mounted, and comminuted conducting material within said chamber, substantially as described.

14. In a telephone-transmitter, the combination with a suitable diaphragm, of a chamber carried thereby, an electrode in said chamber and moving therewith, an independently-supported electrode opposed to said first-mentioned electrode and having a piston-like

movement relatively to said chamber, and comminuted material between said electrodes, substantially as described.

15. In a telephone-transmitter, the combination with a diaphragm, a recess or chamber carried thereby, a supplemental diaphragm, a block secured to the supplemental diaphragm, a support for the block, and means to secure the block in its support in any position, whereby the block may be adjusted in its support by the vibration of the diaphragm and then secured in adjusted position, substantially as described.

16. In a telephone-transmitter, the combination with a suitable sound-receiving diaphragm, of a chamber for the granules carried thereon, an electrode within said chamber and moving with said diaphragm, a supplemental diaphragm adapted to close said chamber, and a second electrode associated with said supplemental diaphragm in an intraperipheral position, substantially as described.

17. In a telephone-transmitter, the combination with a suitable diaphragm, of a chamber for the granules carried thereon, an electrode within said chamber and moving with said diaphragm, a supplemental diaphragm having its periphery secured to the edge of the chamber, and a second electrode associated with said supplemental diaphragm in an intraperipheral position, substantially as described.

18. In a telephone-transmitter, the combination with a diaphragm having a laterally-deflected chamber thereon, of an electrode in said chamber and movable therewith, a supplemental member, a second electrode associated therewith, said supplemental member being adapted to close said chamber and permit the free relative vibration of said electrodes, and comminuted conducting material within said chamber, substantially as described.

19. In a telephone-transmitter, the combination with a cylindrical front piece, of a sound-receiving diaphragm having its central portion forwardly displaced, an electrode mounted in said displaced portion of the diaphragm and adapted to partake of the movement of the center of the diaphragm, an abutment or supporting-bridge rigidly secured to said front piece, a second electrode adapted to be rigidly mounted on said abutment or bridge and opposing said first electrode, a resilient member associated with said second electrode, and comminuted material between said electrodes and confined by said resilient member, substantially as described.

In witness whereof I have hereunto subscribed my name in the presence of two witnesses.

WILLIAM W. DEAN.
